WRINGER

Julian L. Perkins, West Springfield, Mass.

Application January 28, 1936, Serial No. 61,145

4 Claims. (Cl. 68—32)

This invention relates to improvements in wringers or mangles and this application is a continuation in part of an application filed by me on January 8, 1936, Serial No. 58,075, which has matured into Patent No. 2,073,974, March 16, 1937.

The principal objects of the invention are directed to the provision of a wringer which is simple in form and consists of a relatively few parts so as to be economical to manufacture. This is accomplished by the provision of a novel combination and arrangement of parts.

According to one special feature of the invention the wringer includes a frame structure having operating parts associated therewith and a separable shell or shell parts whereby the appearance of the wringer may be changed or varied without the necessity of changing the mechanical features. In this way the mechanical features are not limited to or affected by the appearance of the wringer.

Various other novel objects and advantages of the invention will appear from the following description of the preferred form thereof, reference being had to the accompanying drawings, wherein:

Fig. 1 is a plan view of a wringer embodying the novel features of the invention;

Fig. 2 is a side elevational view of the wringer shown in Fig. 1;

Fig. 3 is a left-hand end elevational view of the wringer shown in Figs. 1 and 2;

Fig. 4 is a view similar to Fig. 3 taken at the right-hand end of the wringer shown in Figs. 1 and 2;

Fig. 5 is a longitudinal sectional elevational view through the wringer shown in Figs. 1 to 4 inclusive;

Fig. 6 is an elevational sectional view on the line 6—6 of Fig. 5;

Fig. 7 is a similar view taken on the line 7—7 of Fig. 6;

Fig. 8 is a sectional elevational view taken on the line 8—8 of Fig. 5;

Fig. 9 is a sectional elevational view taken on the line 9—9 of Fig. 5;

Fig. 10 is a sectional plan view on the line 10—10 of Fig. 9;

Fig. 11 is a similar view taken on the line 11—11 of Fig. 9; and

Fig. 12 is a perspective view of the end cover or casing for the head end of the wringer.

Referring now to the drawings more in detail the invention will be fully described.

The wringer has a head including a horizontal

barrel part 2, a vertical barrel part 4 and an outer end part 12 which is connected to the head part by a longitudinally extending lower member 10. These parts constitute a support for the wringer and may be called a frame.

A part indicated generally by 8 extends upwardly from and is associated with the head which corresponds to the end part 12. A bearing 14 is associated with the vertically extending tubular part 4 and in this a shaft 16 is rotatable. This shaft may be driven from a washing machine mechanism and a driver in the form of a spur gear 18 is fixed on the upper end of said shaft 16. The part 4 may rest on the vertical column of a washing machine as is usual with 15 wringers.

A bushing 20 is rotatable in a part 21 of the head and this bushing is bored to receive a shaft 22. The bushing is splined at 24 to receive a key 26 of shaft 22 so that the shaft 22 may reciprocate in and also drive bushing 20. A pair of gears 28 are rotatable and reciprocable in a bore 29 of the tubular part 2 of the head. These are of the face type having their teeth on adjacent sides.

Pins or the like such as 30 secure the gears 26 to shaft 22 so that they reciprocate and rotate therewith. A collar or hub 32 between gears 26 rotatably receives the shaft 22 and a pin 34 is secured to the collar 32 and extends through an angularly disposed slot 35 in the head (see Fig. 10). The pin and slot function to bring about reciprocating movements of the collar 32, shaft 22 and gears 26 accordingly as the collar is oscillated. In this way the gears are shifted or moved from their neutral position shown in Fig. 5 to an operative engaged position with the driver accordingly as the collar is oscillatable in one direction or the other. A shifter 40 is journaled on the part 21 of the head and this has a rearwardly extending part 42 which is slotted at 44 to receive pin 34 (see Fig. 10) and an upwardly extending part 46 which is provided with a slot 48 (see Fig. 9). As this part 40 is oscillated, the collar 32 is oscillated thereby.

A seat 50 or saddle (see Figs. 5 and 8) is associated with the outer frame part 12 and a yoke 52 in the form of a U is arranged to seat in the saddle 50. A journal part 54 resting in the yoke 52 has a bearing 56 which rotatably receives one end 58 of the shaft of a lower roll 60. A more or less spherical end 62 of the lower roll shaft is received in the bushing 20 of the head. A pin 64 thereof is received in slots 66 in the end of bushing 20. In this way as shaft 22 ro-

tates to rotate the bushing 20 the lower wringer roll 60 is rotated thereby.

Ears 66' are associated with the saddle part 52 and other similar ears are associated with the head (see Fig. 8). Rods 68 are slideable in these ears 66' and around these are compression springs 70 which are disposed between the ears 66' and the heads 72 of bolts 68. Receivers 76 are slideable up and down in the end part 12 and in the head, and the upper threaded ends 11 of the rods 68 are in engagement therewith. The receivers 76 in the head end and in the outer frame part 12 are similarly mounted so that the said receivers are spring-pressed downwardly and move upwardly against the action of the springs. The receivers as in Figs. 6 and 8 have on their adjacent faces vertically disposed slots 80. Locks 82 have studs 84 which are journaled in the receivers 76 so that the locks may swing from the neutral position shown in Figs. 6 and 8 to an angular position relative thereto or to an operative locking position wherein they are at an angle relative to the position shown in said Figs. 6 and 8.

The locks 82 are provided with vertically disposed slots 86 in their adjacent faces and the receivers 76 in their lower sides and on adjacent faces have continuations of the vertically disposed slots 80 (see Figs. 6 and 8). The locks 82 which are associated with the head and with the outer frame part 12 are alike except that the lock associated with the head has a pin 83 extending rearwardly therefrom. This pin 83 is received in the upper slotted end 46 of the shifter 40 so that as this lock is oscillated, it oscillates the said shifter 40.

A separable upper frame 90 (see Fig. 5) has downwardly extending end parts 92. Projections such as 94 for operating locks 82 extend outwardly from the parts 92. An upper wringer roll 96 is preferably journaled, as by bearings 98, on a shaft 100, the opposite ends of which shaft are fixed to the frame parts 92 and extend outwardly therefrom.

This upper frame 90 and roll 96 constitute a unit which may be withdrawn from and inserted in the wringer. The ends of roll shaft 100 and the projections 94 of the frame 90 are receivable in the slots 80 of the receivers and slide into and through slots 86 of the locks 82, when the locks are in the neutral inoperative position shown in Figs. 6 and 8.

As before stated, the frame 90 and its associated roll 96 may be withdrawn from or inserted in the wringer. When inserted in the wringer the upper roll 96 rests on the lower roll 60 as shown in Figs. 5 and 7. The ends of shaft 100 of the upper roll are in the lower part of the slots 80 of the receivers 76, while the projections 94 of the upper frame 90 are in the slots 86 of the lock 82. When so arranged in a neutral inoperative position the frame 90 may be swung about the axis of shaft 100 in one direction or the other so that the projections 94 swing the locks 82 into locking position. In locking position locks 82 are disposed so that grooves 88 thereof are at an angle relative to the position shown in Figs. 6 and 8. The lower ends of the slots 86 instead of being over shaft 100 are at a side thereof and their lower edges 85 ride onto the ends of shaft 100 locking the frame 90 and roll 96 to the spring-pressed receivers.

Prior to swinging frame 90 from inoperative to an operative position, it must be released because it is releasably locked in its inoperative,

neutral position. To accomplish this the following is provided.

A lock bar 100' (see Figs. 5, 6 and 7) has a forward end 102 which is receivable in the vertical slot 80 of the receiver 76 at the head end 5 of the wringer. A lever 108 pivoted at 110 to frame 90, has a forward end 112 and a rear end 114. A rod 104 slideable up and down in the frame 90 carries a manually engageable part or button 106. The lower end of rod 104 rests on the part 112 of lever 108 and a spring 116 seated in the frame 90, as shown, bears on the outer end of the lever 108 and tends to urge the said lever in clockwise direction. A part 118 depending from the lever extends through an opening 120 in the end of the lock bar 100' and a pin 122 passes through the part 118 below the said lock bar 101'.

When the wringer frame is in a neutral inoperative position the forward end of the lock 20 bar is in the slot 80 of the receiver 76. When it is desired however to move the wringer frame 90 to an operative position the rod 104 is depressed to swing lever 108 and withdraw the forward end 102 of the lock bar from the slot. 25 This permits the frame to be swung in one direction or the other.

When the frame 90 is swung from an operative position to an inoperative position and arrives at its neutral inoperative position the lock bar 30 100' slides forwardly into the slot to releasably lock the frame 90 in neutral inoperative position. As stated, when the wringer frame 90 is in an operative position and the locks have been swung thereby to locking position the lower 35 edges 85 of the locks 82 ride up on the ends of the shaft 100 of the upper roll so as to lock the upper roll against the lower roll and then as the upper roll moves away from the lower roll it acts against the springs so that the material being passed through the rolls is subject to 40 the action of the springs.

As previously stated, the head part of the wringer is adapted to rest on a washing machine part such as the column thereof. It is usual that 45 the wringer be rotatable but it is desirable that it be rotated only when the wringer rolls are inoperative. To that end the following is provided.

As shown in Figs. 5, 9 and 11 a lever 140 is fixed to shafts 142 which are journaled in the head 50 and carry manually engageable handles or levers 144. On the forward end of the lever 140 there is a projection 146. The lever 140 in its lower position rests on ledge 154. A detent 148 is slideable up and down in the head as shown in Fig. 5 and it extends upwardly through the lever 140 55 with a head end 152 on top of said lever. A spring 150 around the detent urges the said detent downwardly. This detent is adapted to enter a socket or sockets of a column which supports the wringer for locking the wringer against 60 swinging.

A lower part 41 of the shifter 40 has a slot or notch 148 for receiving the projection 146 of lever 140. When the lever 40 is in an inoperative 65 neutral position, the notch 148 thereof overlies the projection 146 so that the lever 140 may now be swung upwardly to move the detent 148 from locking position. When the wringer is in operation the lever 40 has its part 41 to one side of 70 the position shown in Fig. 1 when the lever 140 may not be elevated since the projection brings up against the lower end of part 41. This is desirable as it prevents the wringer being swung while the rolls are in operation.

As a feature to facilitate the ready and easy assembling of the parts the member 40 is maintained in position for oscillation in the head in the following manner (see Figs. 5 and 9).

5 A slot 160 is provided in the hub of the shifter 40 which when the said part 40 is swung counterclockwise from the position shown in Fig. 9 allows the opening 160 to register with an opening in the bearing part 21 of the head. In this 10 position a lock in the form of a ball 162 is dropped through the opening 160 in part 40 into the opening in said bearing part 21. Then when the 15 part 40 is swung clockwise, the opening 160 is out of register with the ball 162 so that it cannot become displaced. The part 40 is recessed at 164 and the part 20 is provided with an annular groove 166. These permit oscillation of the part 40 and rotation of the part 20.

A drain board 130 between the head and outer 20 end frame of the wringer has lugs 132 at its ends which are seated on lugs 134 of longitudinal member 10 and a projecting part 134 on oscillatable member 40 engages the head end of the drain board so that the drain board is tilted to 25 an inclined position by the member 40. Extensions 11 are provided at the sides of drain board 10.

The features of the wringer of the invention already described pertain to the mechanical construction thereof as well as its operation and according to this invention the ornamental appearance of the wringer is dependent on certain parts associated with the parts described. Therefore certain outer ornamental parts are provided 35 which may be varied to vary the appearance of the wringer without changing its mechanical structure. This is very desirable as it is necessary to change the appearance of wringers frequently but the ornamental appearance is in no way affected by the mechanical construction.

To this end casings such as 176 in Fig. 12 and 40 180 in Figs. 1 to 3 are provided. These are different in appearance but are arranged to fit over the head. These casings are preferably of sheet metal or they may be made as a casting or by a 45 stamping, pressing or other operation. As shown in Fig. 12, the casing has side walls 172, rear wall 174, upper wall 176 and a hood part 178. The side walls 172 at their forward sides are arranged to fit on members 175 of the head and 50 openings such as 177 are provided for screws for fastening the casing to the head. The casing as in Fig. 5 may have a boss 179 which fits in the end of the horizontal bore 28 of the head. This 55 is to centralize and position the casing.

For opposite sides of the wringer there are side parts 182 such as shown in Figs. 1 to 4 inclusive. These have end portions 184 and a horizontally disposed portion 186. These members 182 are 60 preferably of sheet metal or the like so as to be light in weight and may be formed to present a pleasing appearance. In the end parts 184 there are lugs 188 for abutting lugs 190 on the head

and end part 12 of the wringer and through these bolts 192 are passed. These bolts secure the side parts 182 to the wringer and of course may take various forms.

While I have described the invention in great detail and with respect to a preferred form thereof, it is not desired to be limited thereto since many changes and modifications may be made therein without departing from the spirit and scope of the invention. What it is desired to 10 claim and secure by Letters Patent of the United States is:

1. A wringer comprising in combination a frame structure, rolls therein, driving connections for said rolls including an oscillatable shiftable member for engaging and disengaging said driving connections, a bearing on which said shiftable part oscillates, and means associated with said shiftable member and bearing for releasably securing the former to the latter for oscillatory movements including a lock member, and the said bearing and shiftable member being provided with registerable openings and grooves arranged whereby the lock member may be inserted through the opening of the bearing into 25 that of the shiftable member when said member and bearing are in register and ride in said groove to permit oscillatory movements of the shiftable member.

2. A drive means for a wringer comprising in 30 combination, a bearing, driving connections including a shifting member oscillatable on said bearing, the said bearing provided with a socket and the said shifting member provided with an opening registerable with said socket and a circumferential groove, a lock member insertable through said opening into said socket whereby the shifting member may oscillate on the bearing with the lock member in said groove to hold the bearing and shifting member against separation.

3. A wringer comprising in combination, a main frame, a frame oscillatable therein between operative and inoperative positions, rolls associated with said frames, pressure means for said 45 rolls operable as the second named frame is moved to operative position to put the rolls under pressure, movable locks operable by the second-named frame to releasably lock the said frame in operative position, and additional releasable locking means between said frames.

4. A wringer comprising in combination, a main frame having a roll therein, receivers resiliently mounted in said frame, a swingable separate frame unit having a roll therein and parts 55 receivable in the receivers, locks movably mounted on said receivers and movable by the frame unit to releasably lock the same to the receivers with the rolls in operative relation, and additional locking means associated with said frames to releasably lock the separate frame unit against swinging movement.

JULIAN L. PERKINS.
